UNITED STATES PATENT OFFICE.

GEORGE COWLEY, OF RIO, WISCONSIN.

FENCE-WIRE TIGHTENER AND STRETCHER.

Application filed October 8, 1926. Serial No. 140,312.

The present invention appertains to a new and useful device used more particularly for repairing wire fences.

An important object of the invention is to 5 provide a device of the character described which will grip two terminals of wires in firm actuation and draw the same together so that they may be united.

Among the other aims and objects of this 10 invention may be cited the provision of a device of the character described with a view to compactness and convenience and in which the number of parts are few, the construction simple and the cost of production 15 low.

With these and other objects in view, the invention consists in the construction, combination and arrangement of parts as will be hereinafter more fully described, illustrated in the accompanying drawings, and pointed out in the claim hereunto appended.

In the drawing:

Figure 1 is a side elevation of the apparatus embodying the features of my invention.

Fig. 2 is an enlarged detail view showing one lever associated with one bar,

Fig. 3 is a sectional view taken substantially on the line 3—3 of Fig. 1,

Fig. 4 is a detail perspective of the other lever,

Fig. 5 is a view similar to Fig. 2 but showing a modification.

Referring to the drawing in detail, it will 35 be seen that A denotes one of the L-shaped bars and B the other of said L-shaped bars. The bar A includes the long arm 5 which has ratchets on its upper edge 6 and the depending short arm 7 on which is pivotally mounted a clamp member 8 having a shoulder 9. A pivoted clamp element 10 is mounted on the clamp element 8 and has an arcuate cam face provided with teeth as is indicated at 11. The bar B includes the 40 long arm 12 having on its lower edge ratchet teeth 14 and a depending short arm 15 on which is pivoted another member 8 having associated therewith another member 10. The ends of the wires are adapted to be 45 engaged in the clamp structures at the lower terminals of the short arms 7 and 15 as is clearly shown in Figure 1. The bars A have attached thereto a chain and hook structure 17 so that this bar A may be anchored to a post or the like.

A sleeve 18 is slidable on the long arm 5

and has pivotally mounted thereon a lever 19 the lower end of which is pivotally engaged with the extremity of the long arm 12. A dog 20 is pivoted to the lever 19 for engagement with the ratchets 6. A second lever 21 is bifurcated and straddles the bar 5 and is pivoted thereto as at 22 and between its extremities at its bifurcations is provided with a cross element 23 for engagement with the ratchet teeth 14 which may be swung to the dotted line position for releasing the device. A spring 25 is engaged with the lever 21 and with the long arm 5 for normally holding the lever 21 in the 70 full line position shown in Fig. 1, that is, with the cross element 23 engaged with the ratchet teeth 14.

It will be seen that by oscillating the lever 19, the pawl and ratchet structures described 75 will cause a step-by-step movement of the short arms 7 and 15 towards each other for bringing the ends of the wires together so that they may be tied or otherwise secured together.

In Fig. 5 I have shown a modification of the lever 19 wherein a pawl 20' is rigidly attached thereto as is indicated at 27 for engagement with the ratchet 6. In this embodiment no sleeve 18 is used.

From the foregoing, it will be readily apparent that I have provided an efficient and substantial device of the character described and while this specification manifests in detail the preferred constructions of the invention, I do not wish to be understood as limiting myself to the specific details of construction and arrangement of parts herein described and illustrated, as it is manifest that variations and modifications may be resorted to in the features of construction and in the arrangement of parts in the adaptation of the device to various conditions of use without departing from the spirit and scope of the invention. I therefore reserve 90 the right to all such variations and modifications as properly fall within the scope of my invention as hereinafter claimed.

Having thus described my invention what I claim as new is:

A device of the class described including 105 a pair of L-shaped bars comprising long arms having ratchet teeth, said long arms adapted to be disposed one above the other, clamp means pivoted on the extremity of the 110 short arms of the L-shaped bars, a sleeve on the upper long arm slidable thereon, a

lever, a dog engageable with the ratchet teeth of the upper long arms, a pivot pin connecting the sleeve the dog and the lever, said lever being pivotally engaged with the 5 extremity of the lower long arm, a second lever pivoted intermediate its ends to the upper long arm, a cross member on the second lever engageable with the ratchet teeth

of the lower long arm, and a spring associated with the second lever normally holding it in a position so that its cross member engages the ratchet teeth of said lower long arm. 10

In testimony whereof I affix my signature.

GEORGE COWLEY.
